UNITED STATES PATENT OFFICE.

ANTOINE LACROIX, JR., OF BROOKLYN, ASSIGNOR TO THE CO-OPERATIVE BUILDING PLAN ASSOCIATION, OF NEW YORK, N. Y.

DESIGN FOR THE EXTERIOR OF A HOUSE.

SPECIFICATION forming part of Design No. 20,090, dated August 12, 1890.

Application filed July 15, 1890. Serial No. 368,863. Term of patent 7 years.

To all whom it may concern:

Be it known that I, ANTOINE LACROIX, Jr., of the city of Brooklyn, in the county of Kings and State of New York, have invented a new 5 and original Design for the Exterior of a House, of which the following is a specification, reference being had to the accompanying drawings, forming a part thereof.

Figure 1 represents a perspective view of a 10 house showing my design. Fig. 2 represents a horizontal section or plan of the first story. Fig. 3 represents a horizontal section or plan of the second story.

Similar letters of reference designate corresponding parts in all the figures.

A house of this design consists of two stories with an attic third story within a gable roof. The front and one side of the house has an extension, also provided with a gable roof 20 extending at approximately right angles to the first-mentioned roof. The first story on the opposite side also has an extension of about one-half of the width of the house. A piazza with a shed roof extends along the side 25 and front of the house, beginning at the angle formed by the last-mentioned extension and terminating at the front in a porch having a gable roof, and which forms the main entrance to the house. The roof of the extension on the side of the house forms the floor 30 of the balcony on the second story, and at the front of the house in the angle formed by the other extension is another balcony on the second story, all of which will be more particularly described hereinafter with reference 35 to the accompanying drawings.

A B C designate the exterior of the first and second stories and attic. Said portions represented at the front and one side of the house are partly comprised in an extension 40 D, provided with a gable roof d. The main portion of the house has also a gable roof E, extending widthwise thereof and from which the roof d projects at approximately right angles. The first story has a piazza F with 45 a shed roof f, which terminates on one side at about the middle of the house and extends round the front as far as the commencement of the extension D, and finishes with an entrance-porch G, opposite to which are steps 50 L to the ground. The porch is provided with a gable roof g adjoining the shed roof of the piazza. At the rear of the house there is an extension H of the first story, which has a shed roof h. On that side of the house having the piazza the first story is provided with another extension I, whose roof at the second story forms the floor of a balcony i, which extends along the width of such extension. On the second story in the angle formed by 60 the extension D in the front of the house there is a balcony J, covered by a portion of the gable roof d. A dormer-window K projects from the roof E and is provided with a hip roof k. 65

What I claim as my design is—

The design for the exterior of a house, substantially as herein shown and described.

ANTOINE LACROIX, JR.
